Joseph Robinson, New York, N. Y.

Application July 24, 1935, Serial No. 57,795

Term of patent 14 years

To all whom it may concern:

Be it known that I, Joseph Robinson, a citizen of the United States, residing at New York, in the county of New York and State of New York, have invented a new, original, and ornamental Design for Non-Electrical Vaporizer, of which the following is a specification, reference being had to the accompanying drawing, forming a part thereof, in which—

Fig. 1 is a view in elevation, and
Fig. 2 is a top plan view of a non-electrical vaporizer showing my new design.

I claim:

The ornamental design for a non-electrical vaporizer as shown.

JOSEPH ROBINSON.
